UNITED STATES PATENT OFFICE

JOSEPH PRESCOTT BIGELOW, OF LUNENBURG, MASSACHUSETTS

SIGN

Application filed January 11, 1932. Serial No. 585,973.

The device forming the subject matter of this application is a sign, adapted to be placed on or adjacent to a road-way, where men are working, although the device is 5 adapted for other uses which will suggest themselves readily to a person reading this specification. The invention aims to provide a device of the class described which cannot be tipped over by the wind, the sign always 10 keeping a vertical position, so that it can be read without difficulty. Another object of the invention is to provide novel means whereby the legs of the sign may be folded up when the device is not in use.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

In the accompanying drawings:

30 Fig. 1 shows, in vertical elevation, a device constructed in accordance with the invention;

Fig. 2 is a section on the line 2—2 of Fig. 1; Fig. 3 is a fragmental longitudinal section showing a portion of the shaft structure;

Fig. 4 is a fragmental transverse section on the line 4—4 of Fig. 3.

In carrying out the invention, there is provided a base, which as a whole, is marked by the letter B. The base B, comprises legs 1, arranged in pairs, the legs of each pair diverging, when the device is in use, as shown in Fig. 1. At their lower ends, the legs 1 have 45 out-turned feet 2, to promote stability. At their upper extremities, the legs 1 of each pair have oppositely extended, reduced, hook-shaped parts 3, forming transverse shoulders 4, and located side by side. The hook-shaped parts 3 extend hinge-wise

around tubular bushings 5 having outstanding flanges 6 at their ends, the flanges holding the hook-shaped parts 3 side by side, as Fig. 3 will show. The legs 1 of the pairs are connected by transverse braces 7.

The letter S marks a support, which is a composite structure. The support S embodies horizontal shaft sections 9 having their inner ends connected by a cross 10, the outer ends of the shaft sections 9 being 55 mounted to rock in the tubular bushings 5. Endwise movement of the shaft 9—9 in the tubular bushings 5 is prevented by abutment collars 12 held on the shaft sections 9 by securing elements 14, the collars cooperating 60 with the flanges 6 at the inner ends of the bushings 5, as Fig. 3 will show. Into the lower part of the cross 10 is threaded or secured otherwise, the downwardly extended nipple 15, on the lower end of which a cap 16 is threaded, the cap being provided with a hook 17 engaged detachably with an eye 18 on a weight 19. Into the upper part of the cross 10 is threaded a vertical standard 20, the upper end of the standard being threaded, 65 or mounted otherwise, upon a head bar 21 attached by securing elements 22 to the bottom of a fork 23. The upper ends of the arms of the fork 23 are connected by a rod 24. Nuts 25 are threaded on the rod 24 and engage 70 opposite sides of the arms of the fork 23. The fork 23 and the rod 24 form a loop-shaped frame.

A depending sign S is provided, and preferably is made of metal, like the balance of 75 the structure. The sign S may be inscribed in any desired way, as shown at 27. On its upper edge, the sign S has a tubular bearing 26 receiving the rod 24 loosely enough so that the sign can swing backward and forward 80 through the fork 23.

In practical operation, when the device is set up as shown in Fig. 1, the weight 19 tends to keep the sign S in a vertical position, so that it can be read without difficulty. If the wind is strong enough to swing the frame 24—23 a little, against the action of the weight 19, the sign S will still hang vertically, because it is suspended at its upper end, pivotally, by the bearing 26 and the rod 24. Con-

sidered from a different standpoint, the shaft 9 can rotate sufficiently, and the sign S can swing sufficiently, from its upper end, so that the device presents no unyielding area to the wind, of sufficient extent to tip the device over.

When the legs 1 are sprawled apart, as in Fig. 2, sufficiently to afford a firm support, the end of the hook-shaped part 3 on one leg 10 engages the shoulder 4 of the adjoining leg, as shown in Fig. 1, and prevents the legs from spreading apart further than shown in Fig. 2. When, however, it is desired to house the article in small compass, the legs 1 can be swung 15 inwardly toward each other, until their combined thickness is little or no greater than the thickness of any other part of the structure. The hook-shaped parts 3 extend more than half-way around the bearing or bushing 20 5, and, therefore, have a good hold upon it, a hinged connection between the legs and the bushing being at the same time afforded. The general construction of the article is such that it can be made at small expense out of 25 stock parts.

The bushing 5 has three offices. It forms a hinged connection between the upper ends of the legs 1, it forms a bearing for the shaft 9, and because the inner flange 6 on the bushing 30 is interposed between one of the parts 3 and the adjoining collar 12, there is formed, as shown in Fig. 3, an oiling crack 28, through which a lubricant may be introduced upon that part of the shaft 9 which turns in the 35 bearing or bushing 5.

In connection with the folding together of the legs 1, attention is directed to the dotted line showing at 29 in Fig. 4.

Having thus described the invention, what 40 is claimed is:—

1. In a sign board construction, a base, a support mounted to swing on the base with respect to a horizontal axis, means for yieldably limiting the swinging movement of the 45 support, a sign, and means for hingedly connecting the upper portion of the sign to the support, above said axis, for swinging movement about another horizontal axis.

2. In a sign board construction, a base, a 50 support mounted to swing on the base with respect to a horizontal axis, a weight connected to the support, below said axis, and constituting means for yieldably limiting the swinging movement of the support, a sign, and means for hingedly connecting the upper 55 portion of the sign to the support, above said axis, for swinging movement about another horizontal axis.

3. In a sign board construction, a base embodying pairs of diverging legs, a tubular bushing joining the upper ends of the legs of each pair together for hinged movement, braces connecting the legs of one pair with the legs of the other pair, a support including 60 65 a horizontal shaft mounted to rock in the

bushings, a sign carried by the support and disposed above the shaft, means connected with the support, below the shaft, for yieldably limiting the swinging movement of the support and the sign, and means for limiting the longitudinal movement of the shaft in the bushings.

In testimony that I claim the foregoing as my own, I have hereto affixed my signature.

JOSEPH PRESCOTT BIGELOW.
